UNITED STATES PATENT OFFICE.

ROBERT N. FALGE, OF CLEVELAND, OHIO, ASSIGNOR TO GENERAL ELECTRIC COMPANY,
A CORPORATION OF NEW YORK.

TWO-FILAMENT INCANDESCENT LAMP.

Application filed August 17, 1921. Serial No. 492,887.

My invention relates to electric incandescent lamps and more particularly to filament forms for incandescent lamps.

My invention has to do with two-filament lamps and more particularly with such lamps used for projection purposes, as, for instance, in automobile headlights. These lamps usually contain a major filament of high candle-power and a minor filament of comparatively low candle-power and the filaments are coiled and located close together in order to obtain the proper light distribution. In the application of R. F. Strickland of even date here-with, is disclosed an arrangement of the major and minor filaments which permits an accurate and efficient manufacture and which will retain its construction and relative arrangement of parts under the extreme conditions of temperature which arise during the operation of such lamps and of vibration in automobile service. My invention, in one aspect thereof, is an improvement upon the arrangement disclosed in that application.

My invention consists of a substantially uni-directional filament preferably coiled which is mounted preferably with its geometric center substantially coinciding with the geometric center of a second filament which at least partially surrounds the same and is disposed in a plane transverse to the plane of the latter which makes an oblique angle with the line of intersection of the two planes. The plane of the second filament preferably includes the axis of the lamp or is parallel thereto. The coincidence of the geometric centers is preferred as it facilitates the making of a quite accurate adjustment, with the usual mounting equipment, of the position of the lamp with reference to the focus of the parabolic reflector which is ordinarily used, as set forth in the Strickland application.

The disposition of the substantially uni-directional filament at an oblique angle to the plane of the surrounding filament allows the lamp to be so disposed with reference to the reflector that a preponderance of the light rays emanating from the said filament may be caused to encounter a desired section, for instance, the bottom or top of the reflector. This is of considerable advantage in connection with the prevention of glare. I have found that where the straight filament is disposed at an angle of 45° with the plane of the surrounding filament, the latter including or being parallel to the axis of the lamp, a con-

struction is provided which is particularly useful.

I prefer to use a V-shaped form for the surrounding filament which is preferably the major filament making the straight filament the minor filament. The minor filament is preferably mounted in a plane which is substantially at right angles to the plane of the V-shaped major filament, the minor filament making an angle of about 45 degrees with the line of intersection of the two planes. The mid-point of the minor filament substantially coincides with the geometric center of the major filament. As well as being practical and providing a mounting which is rigid and which eliminates sagging and interlocking filament troubles, this construction permits a concentrated distribution of light from the major filament and an effective distribution from the minor filament. The common geometric center is preferably placed substantially in the focus of the usual parabolic reflector of, for instance, an automobile headlamp. The direction of the straight filament with reference to the top or bottom of the reflector will depend on the distribution desired. To cause more rays to strike the more effective portion of the lower half of the reflector the straight filament should incline downwardly toward the front of the reflector and to cause more rays to strike the more effective portion of the upper half of the reflector the straight filament should incline upwardly toward the front of the reflector.

In the accompanying drawing Fig. 1 is an elevation of an incandescent lamp embodying my invention; Fig. 2 is an elevation of the same at right angles to the elevation of Fig. 1; Fig. 3 is an enlarged perspective view of the lamp filaments and supports therefor and Fig. 4 is a diagrammatic vertical section of a reflector having mounted therein a lamp embodying my invention.

The major filament 10 is V-shaped and is mounted upon the leading-in wires 11 and 12 which are carried by the stem 13 of the lamp 14. This filament is of large diameter wire and is closely coiled so as to give a fairly concentrated source of light. It is mounted in the space surrounding the focus of the reflecting equipment with which it is used so that the said focus coincides with the geometric center of the V.

The minor filament 15 is of small diameter filament wire and is coiled to concentrate a

considerable length of wire into a small space. This filament has a substantially uni-directional axis and is mounted upon the leading-in wire 17 and upon the anchor 18 carried by 5 the leading-in wire 12, so that it makes an angle of substantially 45 degrees with the plane of the major filament 10. The geometric center of the minor filament 15 substantially coincides at 19 with the geometric 10 center of the major filament 10.

The parabolic reflector 20 in Fig. 4 has its focus at 21 which is also the location of the coincident geometric centers of the filaments. As shown, the substantially uni-directional 15 filament 15 is inclined downwardly toward the front of the reflector and a preponderance of light rays are thrown against the rear of the lower half of the reflector 20.

Either filament or both may be lighted 20 through the use of the usual controlling means for two-filament lamps. When properly placed in the reflecting equipment each filament will be as much in focus as the other and will give the advantages common to two-filament lamps having both filaments in focus 25 in addition to the specific advantages set forth in the preceding description.

Both major and minor filaments are made of the proper length to obtain the desired distribution of light on the road or, in other 30 words, the proper width of beam. While both of the geometric centers of the filaments may be made to coincide with the focus of the reflector, it may be desirable to have either or 35 both of such centers out of focus in order to obtain the desired light distribution. Any

such arrangement is to be considered to come within the scope of my invention as indicated in the following claims.

What I claim as new and desire to secure 40 by Letters Patent of the United States, is:—

1. An incandescent electric lamp comprising a bulb and two independent filaments of unequal candle power therein, one of said filaments being angular and having its axis substantially coincident with that of said bulb, and the other filament being rectilinear and disposed obliquely to the plane of said angular filament with one portion thereof on one side and the other portion on the other side 50 of said plane, said filaments being confined within a space which is small compared to the dimensions of the bulb and having their geometric centers substantially coinciding.

2. An incandescent electric lamp comprising 55 a bulb and two independent filaments of unequal candle power therein, one of said filaments being angular and having its axis substantially coincident with that of said bulb, and the other filament being rectilinear, disposed in a plane substantially normal to that of said angular filament and extending from one side to the other of the plane of said angular filament at an angle of substantially 45°, said filaments being confined within a 60 65 space which is small compared to the dimensions of the bulb and having their geometric centers substantially coinciding.

In witness whereof, I have hereunto set my hand this 12 day of August, 1921.

ROBERT N. FALGE.
